UNITED STATES PATENT OFFICE.

DAVID WEISS, OF CLEVELAND, OHIO.

COMBINED HEAD-SHIELD AND BAND FOR CIGARS.

1,106,016.

Specification of Letters Patent.

Patented Aug. 4, 1914.

Application filed May 17, 1912. Serial No. 897,849.

To all whom it may concern:

Be it known that I, DAVID WEISS, a citizen of the United States of America, residing at Cleveland, in the county of Cuyahoga and State of Ohio, have invented certain new and useful Improvements in a Combined Head-Shield and Band for Cigars; and I hereby declare the following to be a full, clear, and exact description of the invention, such as will enable others skilled in the art to which it pertains to make and use the same.

This invention relates to improvements in a combined head-shield and band for cigars. The object of this invention is to provide a shield for the head of a cigar for protecting and keeping the same in a sanitary condition, together with a band for carrying the name or trade-mark of the cigar, and to form said band and shield from a single blank so that the shield and band can be applied to the cigar in a continuous operation and in about the same time as it now takes to apply a band.

With this object in view, this invention consists in certain features of construction, and combination of parts, hereinafter described, pointed out in the claims, and illustrated in the accompanying drawings.

In said drawings, Figure 1 shows the blank which when applied to the cigar forms the shield and band. Fig. 2 shows the blank partially applied to the cigar. Fig. 3 is a top plan relative to Fig. 2. Fig. 4 shows the completed shield and band on a cigar.

Referring to the drawings, and particularly to Fig. 1 which shows the blank for forming the shield and band, 10 represents the main part or body-portion of the blank. Said blank is of any suitable flexible thin material, such, for instance, as paper. The left-hand portion of the main part or body 10 has a top edge 11 which is substantially straight and substantially horizontal, and said portion also has a left-hand side edge 12 which slants downwardly to the base of said main part or body. Said main part or body is long enough to surround the cigar to which my improved combined head-shield and band is to be applied, and provided at its base with a band-forming portion 14 which extends longitudinally of said base,—that is longitudinally of said main part or body,—and has its lower edge 15 substantially parallel with the top edge 11 of said main part or body. The band-forming por-

tion 14 terminates at the right-hand end of the main part or body 10 in a tab 16 which at its top edge is free from said main part or body, and said band-forming portion is long enough to render it capable of surrounding the cigar, and the tab 16 is arranged to overlap the opposite end of said band-forming portion upon wrapping said band-forming portion with said main part or body around a cigar. The main part or body 10 terminates at its right-hand end and above the tab 16 in a flap 13 which is arranged at an angle to said main part or body and projects upwardly or outwardly from said main part or body and above and to the right of the top edge 11 of said main part or body and is therefore arranged above said tab and extends above said edge, and said tab is free from said flap and therefore does not interfere with the wrapping of said flap spirally around a cigar. The left-hand side edge 12 of the main part or body 10 is preferably substantially parallel with the flap 13. Said flap is preferably substantially oval-shaped and large enough in dimensions to render it capable of being wrapped spirally around a cigar, so that said flap and the main part or body 10 and the tab 16 of the band-forming portion 14 have the best possible configuration and relative arrangement for enabling the wrapping of said flap spirally around the head-portion of a cigar without forming creases in the spirally wrapped flap and without having portions of said spirally wrapped flap projecting laterally of and outwardly from the cigar. The blank is scored or perforated along the line 17 so that the band-portion can be readily detached from the rest of the blank if it be desired to preserve it.

In Figs. 2 and 4, A indicates a cigar and a in Figs. 2 and 3 represents the head of said cigar.

The operation of forming the shield and adjusting the band on the cigar is as follows:—The blank is placed against the side of the cigar so that the top edge 11 of the body-portion 10 of the blank registers with the tip of the head of the cigar, and said edge therefore forms an index or guide for positioning the blank when applying it to the cigar, as it is important that blanks embodying my invention be correspondingly applied on like cigars in order to present the proper appearance when the cigars are packed in a box. After a blank has been ap-

plied to the cigar the band-forming portion 14 is wrapped around the cigar and the tab 16 on one end of the band-portion is overlapped on and pasted or cemented to the opposite end of the band-portion. The same 5 operation which wraps the band-portion wraps the body-portion of the blank around the head of the cigar, but the flap 13 extends out free as shown in Figs. 2 and 3. The 10 flap 13 is next wound around the cigar in a spiral coil conforming to the shape of the head of the cigar, as shown in Fig. 4, and the end is then twisted beyond the outer extremity or tip of said head as at 18, to prevent 15 unwinding. It will be observed therefore that a cigar protector formed by the blank hereinbefore described has a shield-portion wrapped or wound spirally around and inclosing the head-portion of a cigar, 20 and a band-portion arranged at the inner end of said protector and wrapped around the cigar, and that said band-portion is integral with and readily detachable from said spirally wrapped shield-portion and instrumental in preventing unwinding of said 25 shield-portion.

What I claim is:—

1. A blank for forming a combined band and shield for a cigar, said blank being composed of thin flexible material and comprising a main part or body adapted to be wrapped around the cigar and terminating at its base in a band-forming portion which has the length and arrangement required to surround 30 the cigar upon wrapping said main part or body around the cigar and comprises a tab which forms one end of said band-forming portion, said tab being arranged to overlap the opposite end of said band-forming portion when said band-forming portion surrounds the cigar, the main part or body terminating in a flap which is large enough in dimensions to render it capable of being wrapped spirally around the head-portion of the cigar and twisted at the outer extremity of said head-portion, and said flap projecting above said main part or body and being arranged over the top edge of the aforesaid tab and substantially oval-shaped.

3. A blank for forming a combined band and shield for a cigar, said blank being composed of thin flexible material and comprising a main part or body adapted to be wrapped around the cigar and terminating at its base in a band-forming portion which 75 has the length and arrangement required to surround the cigar upon wrapping said main part or body around the cigar, the main part or body terminating in a flap which is large enough in dimensions to render it capable of being wrapped spirally around the head-portion of the cigar and twisted at the outer extremity of said head-portion, and said flap projecting above said main part or body and being arranged over the top edge of the aforesaid tab and substantially oval-shaped.

3. A blank for forming a combined band and shield for a cigar, said blank being composed of thin flexible material and comprising a main part or body adapted to be wrapped around the cigar and terminating at its base in a band-forming portion which 80 has the length and arrangement required to surround the cigar upon wrapping said main part or body around the cigar, the main part or body terminating in a flap which is substantially parallel with said band-forming portion and terminating in a flap which is large enough in dimensions to render it capable of being wrapped spirally around the head-portion of the cigar and twisted at the outer extremity of said head-portion, and said flap projecting above said main part or body and being arranged at one end of the aforesaid edge, and the aforesaid band-forming portion comprising a tab which forms one end of said band-forming portion and is arranged under said flap and adapted to overlap the opposite end of said band-forming portion when said band-forming portion surrounds the cigar.

In testimony whereof, I sign the foregoing specification, in the presence of two witnesses.

DAVID WEISS.
